UNITED STATES PATENT OFFICE.

JOHN H. SINGER, OF CANTON, OHIO, ASSIGNOR TO THE REPUBLIC STAMPING & ENAMELING COMPANY, OF CANTON, OHIO, A CORPORATION OF OHIO.

DIES FOR FORMING HOLLOW UTENSIL HANDLES.

Application filed March 1, 1923. Serial No. 622,129.

To all whom it may concern:

Be it known that I, JOHN H. SINGER, a citizen of the United States, residing at Canton, in the county of Stark and State of Ohio, have invented certain new and useful Improvements in Dies for Forming Hollow Utensil Handles, of which the following is a specification.

This invention relates to dies for forming sheet metal handles for cooking utensils and similar articles and to the method of forming the same; and the objects of the improvement are to provide a machine including a plurality of sets of dies, into which 15 metal strips or sheets are fed at one end, the finished handles being ejected from the opposite end of the machine; the metal being blanked, folded or beaded, and finally shaped, in continuous operations as the 20 partly finished product is automatically passed through the machine.

The above and ancillary objects may be attained by locating the lower relatively stationary dies in a plane inclined rearward 25 and downward from horizontal at an angle greater than the angle of repose, and providing series of sets of dies for blanking, beading or folding, and finally forming the metal into handles; the upper dies provided 30 with cooperating devices, being mounted for reciprocation perpendicular to the stationary dies; whereby the metal strips or sheets may be fed into the forward upper end of the machine and successively blanked, and 35 folded, and finally shaped by successive operations of the upper dies, the product automatically passing downward and rearward through the machine from one operation to the next, the finished handle being ejected 40 from the lower rear end of the machine.

An embodiment of the invention thus set forth in general terms is illustrated in the accompanying drawings, in which—

- Figure 1 is a side elevation, partly in section, of the upper and lower dies, showing the upper die in the raised position;
 Fig. 2, a top plan view of the lower die;
 Fig. 3, a section on the line 3—3, Fig. 1 and Fig. 2;
 Fig. 4, a section on the line 4—4, Fig. 1 and Fig. 2;

Fig. 5, a section on the line 5—5, Fig. 1

Fig. 6, a longitudinal section through the forming dies showing the same in the operative position;

Fig. 7, a perspective view of one of the blanks;

Fig. 8, a perspective view of the partly completed product, after the folding or beading operation; and

Fig. 9, a perspective view of the finished handle.

Similar numerals of reference refer to similar parts throughout the drawings.

The lower dies are assembled upon the bed or base 1, which is mounted upon a suitable support and inclined at a considerable angle as shown in Fig. 1. The top side of the bed 1 is provided with the longitudinal rib 2 70 provided with the widened portion 3 at the upper or front end of the machine, and with the longitudinally grooved portion 4 at the lower or rear end of the machine.

The lower blanking die 5 is mounted upon the enlarged portion 3 of the longitudinal rib and is provided with the cutting edge 6 shaped to properly form the blank shown at 7 in Fig. 7. This cutting edge is convexed longitudinally as best shown in Fig. 1, in order to produce the proper shearing action. The forward end portion of the lower blanking die 5 is provided with the opening 6^a to permit the blank to pass downward along the inclined surface of the rib 2 to the beading or folding dies.

The lower beading or folding die includes a pair of slidable blocks 8 mounted for transverse movement toward and from each other within the guides 9. The blocks 8 are normally held in the open position as shown in Fig. 2, in engagement with the posts 10, by means of the spiral springs 11 which are connected to the pins 12 upon the blocks 8 and to the hooks 13 connected to the rib 2 or other stationary portion of the die.

As best shown in Fig. 2, it will be seen that the inner longitudinal edges 14 of the blocks 8 are slightly inclined toward each other from front to rear, this being for the purpose of limiting the movement of the blank as it slides downward from the blanking die,

the front end of the blank engaging the edges of the blocks 8 and being held in position to be folded or beaded.

- 5 The lower, inner, longitudinal, edge portions of the blocks 8 are concaved as shown at 15 and the upper outer longitudinal edge portions of the blanks are chamfered or beveled as at 16. Transversely disposed guide plates 17 are fixed to the blocks 8 and provided with the guide openings 18. A tapered guide 19 is mounted beyond the beading or folding die in position to guide the partly completed product shown at 20 in Fig. 8, to the shaping die.
- 10 15 The lower shaping die in the grooved portion 4 of the rib 2 comprises the central depressible plunger 21 having the groove 22 in its upper face and the oscillating blocks 23, each of which is provided with the upper 20 groove 24.

25 The plunger 21 may be provided with any suitable means for normally holding the same in raised position. Each of the rotatable blocks 23 is mounted upon a rocker shaft 26 and is normally held in the raised position by means of the springs 27, which hold the blocks in engagement with the stop pins 28, as shown in Fig. 1. As illustrated in this figure, it will be seen that the grooves 30 and 24 are all in alignment in position to receive the partly finished product 20.

30 35 The knock-out 29 is slidably mounted in the transverse grooves 30 and arranged to be normally held in position over the lower shaping die, as shown in Figs. 1 and 2, by means of the spiral springs 31, which are connected to the pins 32 upon the rear end portion of the knock-out and to the pins 33 carried upon the guide members 30. In the 40 normal position, this knock-out also acts as a guide to guide the partly finished product 20 into the grooves 22 and 24.

45 An aperture 34, beveled at its outer edge as at 35, is formed in the shank 36 of the knock-out. A stop 37 is located at the rear end of the forming die to limit the longitudinal movement of the partly completed product as it is passed into the shaping die.

50 The upper or movable part of the machine includes the head 38 mounted for reciprocating motion toward and from the lower dies in a line perpendicular to the normal plane of the lower dies and carries the upper blanking, folding or beading and shaping dies.

55 The upper blanking die comprises the block 39 shaped to fit snugly within the lower blanking die 5, the longitudinal lower edges of the block being beveled as 40, in order to bend the longitudinal edges of the block 7 as shown at 41.

60 65 The spring pressed plungers 42 are provided in the block 39 for the purpose of engaging the metal strip or sheet in advance of the upper blanking die, to hold the

strip against movement at this time and also to facilitate forcing the blank to the bottom of the lower blanking die, in order that the same may slide downward to the folding or beading die.

70 75 The upper folding or beading device includes two spaced pairs of depending cam members 43, connected to the under side of the head 38 in position to engage the beveled edges 16 of the blocks 8 and slide the blocks transversely toward each other as shown in Fig. 4. A pair of depending fingers 44 are carried by the head 38 between the cam members 43 and provided with enlarged head portions 45 arranged to be received through the openings 18 of the guide plates 17, to assist in moving the blocks 8 back to the normal position, as the head is raised.

80 85 A depending finger 46 is carried by the head 38 in position to be received in the opening 34 formed in the knock-out 29, the lower end of said finger being beveled as at 47 for engagement with the beveled edge 35 of the opening, for the purpose of withdrawing the knock-out form over the lower shaping die, when the head descends, as shown in Fig. 5.

90 95 The upper shaping die 48 is provided with the reduced lower central portion 49 having the longitudinal groove 50, shaped to produce the proper curve in the finished handle, shown at 51 in Fig. 9. The portion 49 terminates in the beveled shoulders 52. A spring pressed plunger 53 is carried in 100 the die 48 and arranged to engage the product in advance of the upper die, and to loosen the finished handle from the upper die as the head is raised.

105 110 115 In operating the machine, a strip of sheet metal of suitable width as indicated at A in Fig. 1, is placed over the lower blanking die in the position shown in said figure, the end of the strip engaging the stop 54. As the head is depressed, a blank as shown at 7 is sheared between the upper and lower blanking dies 39 and 5 respectively, the longitudinal edges of the blank being bent up as indicated at 41, by means of the beveled edges 40 of the upper die 39.

120 125 The blank 7 slides rearward and downward through the opening 6^a and between the blocks 8 of the folding or beading die, being stopped as the forward end of the blank reaches the forward end portions of the blocks 8, which engage the blank and hold the same in position for the next operation.

130 Upon the next downward movement of the head, the blocks 8 are moved toward each other by means of the cam members 43, the bent edge portions 41 of the blank facilitating the folding or beading of the same as the die blocks 8 are brought together as shown in Fig. 4, rolling each edge portion

of the blank as shown at 55, forming the partly completed product 20.

As the head ascends, the die blocks 8 are moved back into the initial position by means of the springs 11, the fingers 44 assuring a positive movement of these blocks in the event the partly finished product should become wedged between the same.

As the product 20 is released, it will slide rearward and downward through the guide 19 and into the grooves 22 and 24 of the lower shaping die, the knock-out 29 guiding the piece into position.

With the next descent of the head 38, the beveled finger 46 engaging the aperture 34 in the knock-out 29, will move the same from over the lower shaping die and the upper shaping die 48 will engage the product, depressing the plunger 21 and rocking the die blocks 23 upon their pivots, the beveled shoulders 52 upon the upper shaping die pressing the end portions of the handle over the beveled portions 57 of the die blocks 23, forming the complete handle, as shown in Fig. 6, with the angular lugs 58 as shown in Fig. 9.

As the head ascends, the die blocks 23 will be rocked back to the initial position by means of the springs 27, and the plunger 21 will be raised to the initial position, carrying the finished handle upward, and into the path of the knock-out, which at this time will be released by the finger 46, the springs 31 shooting the knock-out back into the initial position, striking the finished handle and ejecting the same from the die.

It will, of course, be understood that with each descent of the head, three complete operations will be performed, as a blank will be cut in the blanking dies, the partly finished product will be formed in the folding or beading dies and a complete handle will be shaped in the shaping dies.

I claim:

1. In a machine of the character described, a folding die including a pair of die blocks mounted for reciprocation toward each

other, means for normally holding the die blocks in open position, the outer edges of the die blocks being beveled, apertured guide plates extending outward from the die blocks, a reciprocating head provided with beveled cam members for engagement with the beveled edges of the die blocks to move the blocks toward each other as the head is lowered and fingers upon the head provided with inclined portions for engagement with the apertures of the guide plates to move the blocks apart as the head is raised.

2. In a machine of the character described in claim 1, means for normally holding the die blocks slightly inclined toward each other to limit the movement of a blank entered between the die blocks.

3. A machine for forming utensil handles comprising means for stamping a blank and simultaneously bending the longitudinal edges of the same, means for engaging the longitudinal bent edges and forming the blank into cross sectional B-shape, bending means for bending the partially completed product longitudinally into U-shape with angular outturned lugs at its extremities, the blank being automatically released from each of said means and positioned in the next succeeding means with each operation of the machine.

4. A machine of the character described including an inclined stationary block, a head mounted for reciprocation perpendicular to the block, and a series of cooperating upper and lower dies mounted upon the head and block respectively, and comprising a blanking die for cutting a blank and simultaneously bending the longitudinal edges thereof, a folding die including reciprocating die blocks and a perpendicular reciprocating head for operating the die blocks to engage the bent edges of the blank and fold the blank into substantially B-shaped cross sectional shape and a forming die for bending the partially complete product longitudinally to produce a utensil handle.

JOHN H. SINGER.
